[57] CLAIM

The ornamental design for a recessed lighting fixture, as shown and described.

DESCRIPTION

FIG. 1 is a top, front perspective view of a recessed lighting fixture showing my new design;

FIG. 2 is a left side elevational view thereof on an enlarged scale;

FIG. 3 is a right side elevational view thereof on an enlarged scale;

FIG. 4 is a front elevational view thereof on an enlarged scale, the rear being a mirror image;

FIG. 5 is a top plan view thereof on an enlarged scale; and

FIG. 6 is a bottom plan view thereof on an enlarged scale.

The side and front panels of the lens are shaded to depict transparency.

FIG. 1

FIG. 2

FIG. 3

FIG. 4

FIG. 5

FIG. 6

[57] **CLAIM**

DESCRIPTION

The single FIGURE is a perspective view of a supporting beam for conveyor elements or the like showing my new design. The unseen sides are identical to the sides seen in the drawing and the bottom view is identical to the top side.

U.S. Patent

June 11, 1991

B1 Des. 307,059

**REEXAMINATION CERTIFICATE
ISSUED UNDER 35 U.S.C. 307**

NO AMENDMENTS HAVE BEEN MADE TO
THE PATENT

AS A RESULT OF REEXAMINATION, IT HAS
BEEN DETERMINED THAT:

5 The patentability of the claim is confirmed.
